STEERING HANDLE MEANS

Edgar Jordan, Eau Claire, Wis., assignor to National Pressure Cooker Company, Eau Claire, Wis., a corporation of Wisconsin

Application October 18, 1946, Serial No. 704,041

9 Claims. (Cl. 115—18)

1

This invention relates to outboard motor units, and has to do with the steering handle of such a unit and the mounting means therefore.

Outboard motor units commonly comprise a motor support tube which carries the power head and the propeller and associated parts, this tube being mounted for tilting movement about a substantially horizontal axis, for raising the unit to clear obstructions, or for other purposes, and for turning movement about a substantially vertical axis, in a bearing sleeve or like member, for steering purposes; as is well known. In the operation of the unit considerable vibration, particularly motor torque vibration, is produced. If the steering handle is directly secured to the power head, the vibration incident to operation of the unit is transmitted to the handle. That is objectionable as being both annoying and tiring to the operator, who must hold the handle firmly and continuously while steering. The handle is also used for tilting the unit so as to raise it to clear obstructions, or for other purposes, and should, therefore, be secured to the unit in such manner as not to yield vertically to any appreciable extent, if at all, when downward pressure is applied to the handle.

It has been proposed, in order to avoid objectional transmission of vibration to the handle, to mount the latter by resilient means. In all of such proposed resilient mountings with which I am familiar, the handle mounting means is rather complicated and expensive and is incorporated in the bearing sleeve or like member in which the support tube is rotatably mounted, often necessitating disassembly, to a substantial extent at least, of the support tube and the mounting means therefor, when it is necessary to inspect, repair or replace the steering handle mounting means.

My invention is directed to an outboard motor unit having a steering handle associated therewith in such manner as to be highly efficient with respect to both tilting of the unit and prevention of transmission of vibration to the handle, the handle mounting means being of comparatively simple and inexpensive construction, readily accessible at all times and of such character that the handle structure may readily be removed and replaced as a unit without disturbing any other portion of the outboard motor unit. To that end, the steering handle is mounted on the unit by means providing substantially unyielding connection therebetween for tilting the unit about its horizontal pivot axis, while assuring

2

that substantially all vibration incident to operation of the unit is effectively damped out so as not to be transmitted to the handle. More specifically, the handle is attached to the power head mounting member or flange fixed to the motor support tube, by means accommodating limited turning movement of the handle relative to the mounting member, there being elastic vibration damping means between the mounting member and the handle structure, and the latter and the mounting member having cooperating elements restraining them against relative vertical movement. Further objects and advantages of my invention will appear from the detail description.

In the drawings:

Figure 1 is a side view of an outboard motor unit having applied thereto steering handle means embodying my invention, the mounting sleeve for the support tube being partly broken away and shown in section;

Figure 2 is a sectional view taken substantially on line 2—2 of Figure 3, certain parts being shown in elevation; and

Figure 3 is a fragmentary side view, on an enlarged scale, of the upper end portion of the motor support tube and the motor mounting member secured thereon, with the handle bracket and associated parts carried by the motor mounting member, the handle bracket being broken away.

I have shown my invention, by way of example, as applied to an outboard motor unit 5 comprising a motor support tube 6 to the lower end of which is secured a fitting 7 having bolted thereto an intermediate section 8 and a lower section 9 having the usual skeg 10. The lower section 9 houses the usual gearing for driving a propeller 11 disposed below and adjacent ant cavitation plates 12 at the lower end section 8. The motor support tube 6 is mounted for turning movement in a bearing sleeve 13, conveniently formed in two sections bolted together, this sleeve 13 serving to support the tube 6 and the parts carried thereby for turning movement about a substantially vertical axis. The sleeve 13 is provided, at its upper end, with an arm 14 pivoted at 15 to a clamp bracket 16, for turning movement about a horizontal axis. The bracket 16 is provided with clamp screws 18 and associated parts, whereby the unit is secured to the sill or transom of a boat, as is well known.

A downwardly cupped mounting member 20, which may be of substantially elliptical shape

in plan and is provided at its top with an outwardly extending peripheral flange 21, is fixed on the upper end of the motor support tube 6, conveniently by means of a tubular neck 22 extending downward from member 20 and fitting about and secured on the upper end portion of tube 6. The power head 23, which includes the motor and its various appurtenances, is suitably secured, conveniently by bolting, on the mounting member 20, this power head including a housing or shroud enclosing the motor and its appurtenances, as is known.

The end portion 25 of mounting 21 which is directed forwardly in the forward travel of a boat to which the unit 5 is attached, and may therefore be referred to as the forward end portion, is of rounded or arcuate contour in plan. The member 20 is provided with straight side wall elements 26 extending from the ends of the curved wall of end portion 25. The member 20 is further provided with outwardly extending flanges 27 contiguous to the side wall elements 26 and, at the mid-portion of forward end 25 thereof, with a flange 28 extending outward or forward therefrom and of substantially greater length than either of the flanges 27. The flanges 27 and 28 are disposed below flange 21 in underlying relation thereto, and member 20 is provided with outwardly directed vertical shoulders 29, extending from the rearward ends of elements 26, and defining therewith and with flange 27 and the overlying portion of flange 21, a recess 30.

The forward end portion 25 of member 20 receives head element 31 of a handle bracket 32 comprising part of a handle structure, including a handle member 33 pivoted at its rearward end, at 34, to the forward end of bracket 32. Handle 33 is provided at its forward end with a suitable grip 35, and the handle 33 and bracket 32 are provided with cooperating elements positively limiting relative downward movement of handle 33 beyond its horizontal position shown in Figure 1, while permitting this handle 33 to be turned in to substantially vertical position, as is known.

Head 31 of handle bracket 32 is of rounded or arcuate contour in plan and fits about end portion 25 of member 20, between the upper flange 21 and the lower flanges 27 and 28 thereof. The fit of the head 31 of handle bracket 32 between the flanges of member 20 is a running fit to accommodate turning movement of head element 31, to a limited extent, relative to end portion 25 of member 20, as will appear presently, but there is no appreciable looseness or play between head element 31 and flanges 21 and 27 and 28. Accordingly, with the handle member 33 in its normal horizontal position, by exerting downward pressure thereon, the member 20, and with it the tube 6, may be tilted about axis 15 for raising the unit to clear obstructions and for other purposes.

The head element 31 of handle bracket 32 is provided, at each end thereof, with an inwardly opening notch 37 providing a shoulder 38 opposed to shoulder 29 of member 20. When the handle bracket is mounted on member 20, the notches 37 define with recesses 39 pockets which receive blocks 40 of a suitable resilient material, such as the synthetic rubber known commercially as "Neoprene" which is a polymer of 2-chloro-1,3-butadiene, possessing considerable elasticity and resistant to heat and oil. Any suitable elastic or resilient material may be used, though I preferably use a synthetic rubber such as "Neoprene." Head element 31 of handle bracket 32 is provided

at approximately its midlength with a recess 41 opposed to a recess 42 in end portion 25 of member 20, provided at its end portion with a thickened element 43. A stud 44 is secured in a boss 45 extending inwardly of member 20 from element 43 thereof. This stud 44 extends forwardly or outwardly through a slot 46 in head element 31, of substantially greater length than the diameter of stud 44, providing clearance thereabout permitting movement of head element 31 about end portion 25 of member 20 to limited extent. An abutment 47, preferably in the form of a so-called elastic nut 48, provided at its outer end portion with the plastic insert 49, is threaded on the outer end of stud 44 and restrains handle bracket 32 against outward movement away from end portion 25 of member 20. A block 50 of suitable elastic material, "Neoprene" preferably, is disposed about stud 44 and fits in the recesses 41 and 42 of head element 31 and end portion 25 of the power head mounting member 20. The nut 48 is turned on to the stud 44 sufficiently to hold head element 31 against outward movement away from the rounded end portion 25 of member 20, while avoiding placing the resilient blocks 40 and 50 under appreciable pressure.

It will be seen that the blocks 40 and 50 hold head element 31 of handle bracket 32 spaced outward radially from the corresponding end wall 25 of member 20, thus avoiding metal to metal contact therebetween. In the steering operation, when the handle is turned in either direction, the blocks 40 and 50 are compressed slightly, sufficient to transmit the turning movement to member 20 and to tube 6, and when the turning movement has been completed, for steering purposes, the parts resume their normal relative positions. The blocks 40 and 50, due to their elasticity, readily absorb motor torque vibration and thus eliminate any objectionable vibration of the handle structure from that cause. Also, as previously noted, the flanges 21 and 27 and 28 provide, in cooperation with head element 31 fitting therebetween, convenient means for tilting the motor support tube 6 about its horizontal pivot axis 15, while also providing convenient means for carrying the unit when detached from the boat.

A further important advantage of my invention is that by removing the nut 48 from stud 44, through opening 52 provided in handle bracket 32 for that purpose, the handle structure may readily be moved as a unit from the member 20 without disturbing the mounting of the tube 6 in its sleeve 13, or any other part of the motor unit. By reversing the operation, the handle structure may be quickly and easily replaced. Since the handle bracket 32 is attached to the mounting member 20 below flange 21 thereof, this bracket is curved upward to clear the clamp 16 and associated parts and preferably is also curved toward one side—the left hand side—of mounting member 20, so as to be disposed to best advantage for ease in steering. Briefly, the handle bracket 32 may be suitably formed to meet requirements and, within the broader aspects of my invention, may be of any suitable shape, as will be understood.

It will be understood, by those familiar with this field, that changes in details of construction and arrangement of parts of my invention may be resorted to, without departing from the field and scope thereof, and I intend to include all such variations, as fall within the scope of the appended claims, in this application in which the

preferred form only of my invention has been disclosed.

I claim:

1. In an outboard motor unit, a support tube mounted for turning movement about a substantially vertical axis and for movement about a substantially horizontal axis, a motor mounting member secured on said tube, a handle structure comprising a handle bracket mounted on said mounting member straddling a portion thereof restrained against movement outward therefrom and movable relative to said mounting member substantially horizontally thereabout to limited extent, and elastic cushion means confined between said member and said bracket yieldingly resisting said movement of said handle bracket about said mounting member.

2. In an outboard motor unit, a support tube mounted for turning movement about a substantially vertical axis and for movement about a substantially horizontal axis, a motor mounting member secured on said tube, a handle structure comprising a handle bracket open at its inner end mounted on said mounting member straddling a portion thereof restrained against movement outward therefrom and movable relative to said mounting member substantially horizontally thereabout to limited extent, said bracket being restrained against vertical movement relative to said mounting member, and elastic cushion means confined between said member and said bracket yieldingly resisting said movement of said handle bracket about said mounting member.

3. In an outboard motor unit, a support tube mounted for turning movement about a substantially vertical axis and for movement about a substantially horizontal axis, a motor mounting member secured on said tube, a handle structure comprising a handle bracket mounted on said mounting member straddling a portion thereof restrained against movement outward therefrom and movable substantially horizontally thereabout to limited extent, said bracket and said mounting member having cooperating means restraining them against relative vertical movement, and means yieldingly resisting said movement of said handle bracket about said mounting member.

4. In an outboard motor unit, a support tube mounted for turning movement about a substantially vertical axis and for movement about a substantially horizontal axis, a motor mounting member secured on said tube having a portion substantially arcuate in plan, a handle structure comprising a handle bracket mounted on said mounting member restrained against outward movement therefrom and movable substantially horizontally thereabout to limited extent, said bracket having a head element substantially arcuate in plan extending about said arcuate portion of said mounting member, and means confined between said mounting member and said bracket head element yieldingly resisting said movement of the latter.

5. In an outboard motor unit, a support tube mounted for turning movement about a substantially vertical axis and for movement about a substantially horizontal axis, a motor mounting member secured on said tube having a portion substantially arcuate in plan provided with vertically spaced outwardly projecting flanges, a handle structure comprising a handle bracket having a head element substantially arcuate in plan fitting between said flanges and extending about said arcuate portion of said mounting

member, means attaching said bracket head element to said arcuate portion of said mounting member restraining it against outward movement therefrom while accommodating movement to limited extent of said bracket head about said arcuate portion of said mounting member, and means confined between said arcuate portion of said mounting member and said bracket head element yieldingly resisting said movement of the latter.

6. In an outboard motor unit, a support tube mounted for turning movement about a substantially vertical axis and for movement about a substantially horizontal axis, a motor mounting member secured on said tube having a portion substantially arcuate in plan provided with vertically spaced outwardly projecting flanges, a handle structure comprising a handle bracket having a head element substantially arcuate in plan fitting between said flanges and extending about said arcuate portion of said mounting member, means attaching said bracket head element to said arcuate portion of said mounting member restraining it against outward movement therefrom while accommodating movement to limited extent of said bracket head element about said arcuate portion of said mounting member, the latter being provided at the ends of said arcuate portion thereof with outwardly extending shoulders spaced from the ends of said bracket head element defining with said flanges recesses, said bracket head element having inwardly opening notches at its ends overlapping said recesses forming therewith pockets having end shoulders spaced from said shoulders of said mounting member, and elastic cushion members mounted in said pockets confined between said shoulders thereof yieldingly resisting said turning movement of said bracket head element.

7. In an outboard motor unit, a support tube mounted for turning movement about a substantially vertical axis and for movement about a substantially horizontal axis, a motor mounting member secured on said tube having a portion substantially arcuate in plan provided with vertically spaced outwardly projecting flanges, said arcuate portion of said mounting member having an outwardly opening recess at about its midlength and an outwardly extending shoulder at each end, said shoulders and said flanges defining outwardly opening recesses, a handle structure comprising a handle bracket having a head element substantially arcuate in plan extending about said arcuate portion of said mounting member between said flanges thereof with its ends spaced from said shoulders, said head element having at about its midlength an inwardly opening recess opposed to said recess at the midlength of said arcuate portion of said mounting member, said head element being provided at each end thereof with inwardly opening notches overlapping said end recess of said mounting member forming therewith pockets having end shoulders spaced from said shoulders of said mounting member, means restraining said bracket against movement outward from said mounting member comprising a stud secured thereto passing through said opposed recesses thereof and through said head element with clearance between the latter and said stud accommodating limited movement of said head element about said arcuate portion of said mounting member, a block of elastic material fitting in said opposed recesses about said stud, and blocks of elastic material fitting in said 75 pockets, said blocks yieldingly resisting move-

ment of said bracket about said arcuate portion of said mounting member.

8. In an outboard motor unit, a support tube mounted for turning movement about a substantially vertical axis and for movement about a substantially horizontal axis, a motor mounting member secured on said tube having a portion substantially arcuate in plan provided with vertically spaced outwardly projecting flanges, said arcuate portion of said mounting member having an outwardly opening recess at about its midlength and an outwardly extending shoulder at each end, said shoulders and said flanges defining outwardly opening recesses, a handle structure comprising a handle bracket having a head element substantially arcuate in plan extending about said arcuate portion of said mounting member between said flanges thereof with its ends spaced from said shoulders, said head element having at about its midlength an inwardly opening recess opposed to said recess at the midlength of said arcuate portion of said mounting member, said head element being provided at each end thereof with inwardly opening notches overlapping said end recess of said mounting member forming therewith pockets having end shoulders spaced from said shoulders of said mounting member, means restraining said bracket against movement outward from said mounting member comprising a stud secured thereto passing through said opposed recesses thereof and through said head element with clearance between the latter and said stud accommodating limited movement of said head element about said arcuate portion of said mounting member, a block of

5 elastic material fitting in said opposed recesses about said stud, and blocks of elastic material fitting in said pockets, said blocks spacing said head element away from said arcuate portion of said mounting member and yieldingly resisting movement of said bracket about said arcuate portion of said mounting member.

9. In an outboard motor unit, a support tube mounted for turning movement about a substantially vertical axis and for movement about a substantially horizontal axis, a motor mounting member secured on said tube, a handle structure comprising a handle bracket open at its inner end mounted on said mounting member straddling a portion thereof restrained against movement outward therefrom and movable relative to said mounting member substantially horizontally thereabout to limited extent, and means yieldingly resisting said movement of said handle bracket about said mounting member.

EDGAR JORDAN.
